UNITED STATES PATENT OFFICE.

PAUL M. MIESSNER, OF ALTON, ILLINOIS.

BLIND-STOP.

SPECIFICATION forming part of Letters Patent No. 379,120, dated March 6, 1888.

Application filed December 28, 1887. Serial No. 259,215. (No model.)

To all whom it may concern:

Be it known that I, PAUL M. MIESSNER, a citizen of the United States, residing at Alton, in the county of Madison and State of Illinois, have invented certain new and useful Improvements in Stops for Inside Blinds, of which the following is a full and clear description, reference being had to the accompanying drawings, forming a part of this specification, in to which—

Figure 1 represents an inside blind having my improved stop applied thereto. Fig. 2 is a perspective view of the stop.

My invention relates to means for adjusting the slats of blinds and of holding the slats in their adjusted positions; and my invention consists in the improved blind-stop, herein-after described and claimed.

To enable others skilled in the art to make and use my invention, I will now describe the manner in which I carry the same out.

In the said drawings, A represents a blind of any well-known construction, having the usual pivoted slats, *a*, and the vertical bar *b*, to which said slats are connected. To the lower rail, *c*, of the blind is pivotally secured the lower end of a plate, B, having its upper or free end provided with a flange, C, at right angles to the body of the plate, and provided with a series of step-like projections, *d*, upon which the vertical bar *b* of the blind is supported. The flange C at the uppermost step also projects slightly beyond the body of the plate, as shown at *e*, and the lower rail of the blind is provided with a curved slot or groove, *f*, struck from the pivotal center of the plate, and into this groove or slot the projection *e* passes when the plate B is thrown down out of engagement with the vertical bar *b*. The lower end of the curved slot therefore serves

as a stop for the plate, and yet holds said plate in a position where it may be readily moved up under the bar *b*.

From this description it will be seen that when increased light or ventilation is desired the pivoted plate is adjusted so that the bar *b* may rest upon either of the lower steps or projections; but if it be desired to shut out the light from the room or reduce the volume of air passing thereto the plate is adjusted until the uppermost step is brought under the bar *b*. In this latter position the slats will not only be closed against each other, but the whole series of slats will be held in a locked position by the plate or bar. It is evident, therefore, that I am enabled to regulate the amount of light or air passing into a room by the simple adjustment of the plate B, and at the same time said plate holds the slats in their adjusted positions against accidental displacement.

Having thus described my invention, what I claim as new, and desire to secure by Letters Patent, is—

1. The combination, with a blind having pivoted slats and a connecting-bar, of a pivoted plate having a series of step-like formations upon which said bar is supported, whereby the slats are adjusted, substantially as herein described.

2. The blind having pivoted slats, a connecting-bar, and a lower rail having a curved groove or slot, in combination with a pivoted plate having step-like formations upon its upper end and a flange, *e*, adapted to engage the arched groove or slot in the lower rail, substantially as and for the purpose set forth.

PAUL M. MIESSNER.

Witnesses:

LUCAS PEIFFENBERGER,
GEO. A. GINTER.

Correction in Letters Patent No. 379,120.

It is hereby certified that in Letters Patent 379,120, granted March 6, 1888, upon the application of Paul M. Miessner, of Alton, Illinois, for an improvement in "Blind-Stops," an error appears in the printed specification requiring correction as follows: In line 75, the word "armed" should read *curved*; and that the said Letters Patent should be read with this correction therein that the same may conform to the record of the case in the Patent Office.

Signed, countersigned, and sealed this 13th day of March, A. D. 1888.

[SEAL.]

D. L. HAWKINS,
Assistant Secretary of the Interior.

Countersigned:

R. B. VANCE,
Acting Commissioner of Patents.
